MICRO-VAPOR PRESSURE APPARATUS

August Y. Mottlau, Clark, N. J., assignor to Esso Research and Engineering Company, a corporation of Delaware

Application December 5, 1955, Serial No. 550,922

1 Claim. (Cl. 73—53)

The present invention relates to an apparatus for measuring the vapor pressure of liquids. Particularly, the invention relates to the determination of the vapor pressure of volatile, non-viscous liquids, specifically including petroleum products. The invention further relates to means for making such vapor pressure determination wherein samples of extremely small volumes are employed. According to the present invention, sample volumes of about 1 milliliter may be employed, as compared with sample volumes of as much as 130 milliliters, or more, when conventional systems are employed.

A standard method of test for vapor pressure of volatile liquids of the nature now contemplated, is that known as the Reid Method, as set forth by the American Society for Testing Materials, Philadelphia, Pennsylvania, and designated as A. S. T. M. D. 323-52. Although this method is currently accepted as standard, apparatus now contemplated is less cumbersome, less subject to errors, and employs a sample handling means which markedly reduces volatility, loss and variation. The apparatus of the present invention further provides a reproducible standard deviation of ± 0.022 p. s. i., as compared with the standard deviation in the order of 0.5 p. s. i. attainable by conventional methods.

It is an object of the present invention to provide an apparatus for making of vapor pressure determinations which is highly accurate, but simply and rapidly accomplished. It is also an object of the invention to provide an apparatus which may be employed to produce results which are readily correlated with the results produced by the Reid Method, and which may be employed accurately to predict Reid Vapor Pressure values. It is a further object of the invention to provide an apparatus suitable for employment in making Micro Vapor pressure determinations, including an evacuable sample receiving chamber, and means for maintaining the volume and temperature of such chamber substantially constant.

The invention and its objects may be more clearly understood from the following description, when it is read in conjunction with the accompanying drawings in which

Fig. 1 is a schematic illustration of the apparatus in side elevation and partly in vertical section.

Fig. 2 is an enlarged view in side elevation and partly in vertical section of an accessory part of the apparatus of Fig. 1 in its functional relation to the structure thereof.

Figs. 3 and 4 are similar views in vertical section of other accessory parts of the apparatus of Fig. 1 in their functional relation thereto.

Referring now to the drawings, in Fig. 1, the numeral 1 designates an evacuable chamber which, as shown includes a dependent conduit leg portion 2 and side arm portion 3. The leg portion 2 is provided with a two way valve 4 adapted for alternate communication between the leg 2 and one of two conduits 5 and 6. The conduit 5 provides means for draining the chamber 1. The conduit 6 is connected to a vacuum pump 7 through a trap 8 later referred to.

2

The side arm portion 3, as shown, is formed integrally with one leg 9 of a U-tube mercury manometer, communicating directly therewith. In general, the side arm portion 3 and the upper end of the leg 9 may be considered as meeting in a horizontal plane common to an indicia mark designated by the numeral 10, the arm 3 extending upwardly therefrom to form an inverted U-bend connection with the chamber 1 intermediate the upper and lower ends thereof. The operating capacity of the chamber 1 is defined between the mark 10 and a similar mark at an intermediate level of the conduit 2 which is designated by the numeral 19. The upper end of the leg 9 extends downwardly from the terminal end of the arm 3 to form an enlargement or bulb 11, having a capacity or volume substantially equal to the volume of the chamber 1. Downwardly beyond the bulb 11, the leg 9 is provided with two valves 12 and 13 respectively disposed in vertically spaced relation, one to another, for purposes later described. Beyond the valve 13, the leg 9 communicates directly with the other and second leg 14 of the U-tube manometer through a U-bend portion 15. At its upper end, the second manometer leg opens directly into the surrounding atmosphere.

At its lowermost level, the U-bend portion 15 is provided with a dependent nipple 16 which provides a coupling means for a flexible conduit 17, attached at one end to the nipple. At the other end, the conduit 17 is attached to an open reservoir bulb or container 18. The manometer as well as the container 18 and conduit 17 are adapted to receive and contain a volume of mercury adequate for the purposes later indicated and described. In effect, the container 18 and conduit 17 provide a third manometer leg of variable height, whereby the height of the columns of mercury in the other two legs may be varied as required according to the present invention. In the apparatus illustrated by Fig. 1, an elongated strip of mirror glass is provided as a backing for the leg 14. This strip of glass is designated in the drawing by the numeral 20. As shown, it is provided with a vertical series of horizontal indicia markings adapted to indicate the height of a column of mercury in the leg 14 in centimeters.

As shown in Fig. 1, the upper end of the chamber 1 is closed by means of a partition 21, the walls of the chamber 1 extending upwardly beyond the partition to form a receptacle or container 22. The partition 21 is provided with an orifice 23 opening between the container 22 and the chamber 1. Inasmuch as the system contemplated according to the present invention is a mercury system, the orifice 23 is a "mercury orifice," namely, one which is gauged to inhibit the passage of mercury therethrough by gravity under any predetermined head of a body of mercury which may be contained in the receptacle 22 therefor. The orifice 23, by reason of its size and character also tends somewhat to restrict or inhibit flow when a pressure differential may be imposed across the orifice by evacuation of the chamber, or by the vapor pressure of a material introduced into the chamber. A positive seal is provided, however, by means of a plug element 24 adapted to fit the orifice.

As shown more clearly in Fig. 2, the orifice 23 is preferably ground into the partition 21 to provide a substantially inverted conical passageway having a predetermined apex angle. The plug element 24 is a rod-like member provided with a tip portion adapted to match and be seated in the orifice 23. The tip portion may be ground or formed for such purpose or, as shown, may be provided with an added conically shaped sleeve 26 of a material such as plastic to provide the desired seal with the orifice wall. Preferably, the plug element is weighted, as by a superposed housing filled with shot 27.

The housing, as shown, is closed by means of a stopper 28, including a handle 29.

The accessory part as illustrated by Fig. 3 is comparable to that illustrated in Fig. 2, except that for the plug element 24, there is substituted a tubular element 31. The tubular element 31 is similarly provided with a shaped tip portion 32 and a seal sleeve 33, however, as well as with a housing 34 containing shot 35 as weighting means. The element 31 extends through the housing 34 and a closure 36 therefor to provide a handle portion 37. The part as shown by Fig. 3 is more specifically designated as a vacuum breaker, and its function is later described.

With further reference to Fig. 1, the chamber 1, and including at least a portion of the associated mercury receptacle 22 and the side arm portion 3, as well as at least a portion of the upper ends of dependent conduit 2 and manometer leg 9 are enclosed in a fluid reservoir housing 41. The housing 41 is provided for circulation of a heat exchange fluid therethrough as by means of inlet and outlet conduit connections 42 and 43 respectively. The housing is also provided with a necked orifice 44 adapted to receive a thermometer 45 passed therethrough and held in fluid tight relation by means of a stopper 46.

The accessory part as shown by Fig. 4, is a means for introducing a liquid sample into the chamber 1 after evacuation thereof. As shown, this means comprises a closed mercury bulb 51, having side arm conduit portion 52 opening therefrom at the upper end. An inverted U-shaped pipette having opposite vertical leg portions 53 and 54 of unequal length is associated with the bulb, with the shorter leg portion 53 extended through the upper end of the bulb, in fluid tight relation thereto, and downwardly therein into closely spaced relation to the lower end of the bulb. The lower end of each leg portion is provided with a special tip portion. The tip 55 of the leg portion 53 has a capillary bore of such small diameter that mercury contained in the bulb 51, and indicated there by the numeral 56, cannot enter the bore unless a pressure equivalent to from about 10 millimeters to about 20 millimeters of mercury above atmospheric pressure is applied to the bulb through the side arm 52. The tip 57 of the leg portion 54 is drawn and ground to fit the orifice 23 in the partition 21, and to provide a substantially sealed joint therewith when the tip is inserted in the orifice. The tip orifice is preferably gauged to a diameter of about 0.15 millimeter. The pipette legs 53 and 54, as well as the cross-over connection between them, have a capillary bore 58 slightly larger than that of the tip portion 55. In addition, in the leg portion 53, the bore is enlarged as at 59 to form additional capacity for the pipette. This capacity is proportionally related to the volume of the chamber 1 of Fig. 1. In the apparatus contemplated, the pipette capacity is gauged to a volume about one-fifth that of the chamber 1 as defined between the junction of side arm 3 with the upper end of the manometer leg 9 and a predetermined intermediate level in the dependent conduit 2. In Fig. 1, this intermediate level is designated by the numeral 19.

In employing the apparatus as illustrated and described, a level of mercury is first established in the receiver 22 such as to provide a head which in cooperation with the plug element, will balance a pressure in the chamber 1 substantially equal to the estimated vapor pressure of a liquid to be tested.

With valves 12 and 13 open, and valve 4 turned to provide communication between conduits 2 and 5, mercury is introduced into or withdrawn from the manometer by means of the reservoir 18 and conduit 17 to provide an upper level in the leg 9 which is just above the valve 13. The valve 13 is then closed. By vertical adjustment of the reservoir 18, the level of the mercury column in the leg 14 is brought to a level about seventy-six centimeters below the indicia mark 10 at the upper end of leg 9. At this level, the distance between the level of mercury in leg

14 and the level of mark 10 is approximately equal to the height of a mercury column exerting a pressure of one atmosphere.

With plug 24 in the orifice 23, valve 4 is turned to connect the conduit 2 with vacuum pump 7 through the trap 8. With the pump connected, the pressure in the system including chamber 1, conduit 2, side arm 3, and leg 9 above the valve 13 is reduced to or below that of approximately 0.5 millimeter of mercury. At this point, the valve 13 is opened slowly to permit mercury to enter from the reservoir 18 and as may be required to exactly position the upper level of mercury in the leg 9 at the mark 10. To do this, pumping is continued while the reservoir 18 is raised or lowered to introduce or withdraw mercury to or from the manometer leg 9. Valve 4 is then closed and the plug 24 is raised in order to introduce mercury from the container 22, to a level in the leg 2 at the mark 19. At this point, the level of mercury in the leg 9 is checked and reestablished at the mark 10 if necessary. The level of mercury in the leg 14 is then recorded. The valve 12 is then closed and the apparatus is ready for introduction of the sample liquid into the chamber 1.

The liquid sample to be tested is prepared according to the procedure specified for the Reid method, under the above referred to specification ASTM D. 323-52, and the temperature of the water circulating through the housing 41 previously has been brought to a substantially constant temperature of 100° F. With the sample prepared as specified, the pipette of the accessory part shown in Fig. 4 is filled with mercury by exerting the required pressure through the side arm 52 upon the mercury contained in the mercury bulb 51. Due to the greater length of the arm 54 over the arm 53, when the bore of the pipette is filled with mercury there will be no reverse flow thereof as long as the tip 57 is retained at a level lower than that of the tip 55. In such a position, the tip 57 is dipped into the sample and with the tip 57 covered by the sample, the pipette is then slightly tilted so as to effect an unbalanced condition of the mercury in the bore 58 causing the mercury to flow back into the mercury bulb 51, while at the same time drawing into the pipette a portion of the liquid sample. As previously stated, the pipette bore is gauged to equal about $\frac{1}{5}$ the volume of the chamber 1, and in the operation contemplated, with the chamber 1 having a capacity of about 5 milliliters plus or minus 0.03 milliliter, the capacity of the pipette bore should be about 1.0 milliliter plus or minus 0.003 milliliter, or $\frac{1}{5}$ the internal volume of the chamber 1. With the sample contained in the pipette, the leg 54 is introduced into the mercury contained in the receptacle 22 and withdrawing the plug element 24, the tip 57 of the leg 54 is quickly inserted into the orifice 23. At the pressure existing in the chamber 1, the sample contained in the pipette is then drawn into the chamber, being replaced in the pipette bore by mercury from the mercury bulb 51. With the sample discharged into the chamber, the pipette is withdrawn from the orifice 23 and replaced by the plug element 24. It is to be expected that during this operation, a small amount of mercury may be drawn into the chamber from the receptacle 22 and also from the bulb 51 through the pipette 54. This mercury will pass downwardly into the conduit 2 and after introduction of the sample may be withdrawn therefrom to re-establish the mercury level in the conduit 2 by briefly reconnecting the conduit 2 to the vacuum pump 7 through the valve 4, conduit 6 and trap 8.

The valve 12 is now opened slightly while raising the mercury reservoir 18 and thereby introducing mercury into the leg 14, raising the level therein to balance the pressure of the chamber 1 as produced by the vapor pressure of the sample liquid therein and to maintain the level of the mercury in the leg 9, coincident with the mark 10. When steadiness of the level of mercury in the

leg 9 indicates that an equilibrium pressure has been reached, the level of mercury in the leg 14 is again recorded. The difference between the initially recorded level of mercury in the leg and that recorded after equilibrium pressure has been achieved is indicative of the vapor pressure of the sample liquid and may be directly read as the pressure of the column of mercury above the initially recorded level in the leg 14.

The apparatus may be employed, according to the method described, for testing successive samples when prepared in the manner now described. The valve 12 is first closed in order to maintain the predetermined volume of the chamber 1, and substantially to avoid entrance of vapors from the first sample into the leg 9. The plug 24, is then replaced with the vacuum breaker 31, shown in Fig. 3, and the valve 4 turned to establish communication between the leg portion 2 and the conduit 5. When any remaining liquid portion of the previously tested sample has been drained from the chamber 1, through the conduit 5, suction may be applied to the conduit 5. In this manner any remnants of the previously tested sample may be evaporated from the walls of the chamber. The vacuum breaker 31 may then be replaced by the plug 24, and the apparatus is then ready for another testing operation substantially as already described.

Inasmuch as the testing procedure is initiated with a pressure in the chamber 1 substantially below atmospheric pressure, in order to translate the results obtained to terms of Reid Vapor Pressure, allowance must be made for the partial pressure of air dissolved in the test sample. In other words, the difference, in millimeters of mercury, between the initially recorded level of mercury in the leg 14 and the final level therein, represents the vapor pressure of the sample itself plus the partial pressure of the air dissolved in the sample introduced. This air may be presumed to have come out of solution at the reduced pressure, of the test chamber.

As a first step in such translation of values, the numerical value of the mercury level difference in millimeters is multiplied by 0.01934 to convert the total vapor pressure of the sample evidenced and expressed in millimeters of mercury to a pressure value expressed in pounds per square inch. This pressure in pounds per square inch is designated as MVP (micro vapor pressure). This value is substituted in the following equation to obtain a predicted Reid Vapor Pressure (PRVP): $PRVP = 0.9096 (MVP) - 0.35$.

Although the apparatus has been described with particular reference to vapor pressure determinations wherein in the chamber 1 is to be maintained at a temperature of 100° F., the operation may be conducted at higher or lower temperatures where the materials tested may have either extremely low or extremely high vapor pressures. Also, prior to introduction into the testing apparatus these materials may be initially heated or refrigerated as required to facilitate accomplishment of the determination.

10 What is claimed is:

An apparatus for determining the vapor pressure of vaporizable liquids, comprising a sample receiving chamber, a first conduit connection communicating with and dependent from the bottom of said chamber, means for introducing mercury through said chamber into said dependent conduit connection including a mercury orifice opening into said chamber and a closure for said chamber, a second conduit connection communicating with said chamber in vertically spaced relation to said first 15 conduit connection, a U-tube manometer in direct communication with said second conduit connection through the upper end of a first leg portion of said U-tube, the second leg portion of said U-tube extending upwardly beyond the connection between said second conduit and said first leg, heat exchange means including a housing and means for circulating a heat exchange fluid there-through disposed to enclose said chamber said second conduit connection and at least that portion of said first conduit connection immediately adjacent said chamber, 20 means for introducing and withdrawing mercury into said U-tube, said means adapted to establish and maintain opposed columns of mercury in said U-tube wherein the upper end of the column of mercury in said U-tube first leg substantially limits the volume of said chamber, 25 means for evacuating said chamber, means for introducing a sample portion of said liquid into said chamber through said mercury orifice, and means for indicating the upper surface level of mercury in the second leg portion of said U-tube manometer.
